DRINKING FOUNTAIN FOR POULTRY

Filed Aug. 13, 1928

UNITED STATES PATENT OFFICE

ADOLPH R. HOEFT, OF EVANSTON, ILLINOIS, ASSIGNOR TO HOEFT & COMPANY, INC., OF NORTH CHICAGO, ILLINOIS, A CORPORATION OF ILLINOIS

DRINKING FOUNTAIN FOR POULTRY

Application filed August 13, 1928. Serial No. 299,145.

This invention relates to improvements in drinking fountains for poultry and it consists of the matters hereinafter described and more particularly pointed out in the appended claims.

The primary object of the invention is to provide a drinking fountain of this kind including end frames or plates, a drinking pan and a reservoir, which reservoir is so mounted in the end frames or plates that it may be positioned either to automatically feed water through its filling spout into the drinking pan as the water therein is depleted or to present said spout in a position convenient for cleaning out and refilling the reservoir.

Another object of the invention is to provide a fountain structure of this kind wherein the end frames or plates have broached bearing openings for the trunnions of the reservoir, which trunnions have opposed flat sides, so that the reservoir will stand without swaying in said frames or plates, either in its pan feeding position or in the position making the reservoir easy of access for cleaning and refilling.

These objects of the invention as well as others together with the many advantages thereof will more fully appear as I proceed with my specification.

In the drawings:

Fig. 1 is a perspective view of a drinking fountain for poultry embodying my invention.

Fig. 2 is a longitudinal vertical sectional view through the same on an enlarged scale.

Fig. 3 is a transverse vertical sectional view therethrough as taken on the line 3—3 of Fig. 2.

Fig. 4 is a fragmentary detail view in elevation of the top end part of one of the end frames or plates and illustrates the manner in which the associated trunnion of the reservoir bears in an opening therefor in said frame or plate.

Fig. 5 is a detail vertical sectional view on an enlarged scale as taken on the line 5—5 of Fig. 3.

Fig. 6 is a perspective view of a pin employed in connection with each of the reser-

voir trunnions to lock the same in place in the top ends of said frames or plates which are held against spreading thereby.

Referring now in detail to that embodiment of the invention illustrated in the accompanying drawings; 1—1 indicates the end frames or plates of the fountain, 2 indicates the reservoir thereof and 3 indicates the drinking pan all preferably made of galvanized iron.

Each end frame or plate which stands upright, is substantially A-shaped and includes a body 4 and diverging legs 5—5 all bounded by an outwardly extending flange 6 to impart stiffness and rigidity to the plate. In the apex or top end of said plate is formed an opening 7 defined by an inwardly extending flange 8 and the bottom portion of said opening is horizontally flattened as at 9 as best shown in Fig. 4. 10—10 indicates a pair of inwardly extending, laterally spaced apertured ears, punched from the body of plate in a plane a short distance above the legs. The purpose of said ears will later appear.

The reservoir 2 is in the form of a horizontally disposed hollow cylinder and consists of tubular body 11 and closed ends or heads 12—12 secured thereto in any suitable manner. Each head has an axially disposed offset portion 13 to which is secured an associated trunnion 14 having oppositely disposed flat sides 15—15. Preferably, said trunnion is formed from sheet metal and includes a radial flange 16 at its inner end which engages with and is securely fixed to the offset portion 13 of the associated head in a water-tight relation. With respect to said trunnion, it is pointed out that it is of a diameter a trifle less than the opening 7 in each end plate when the same is measured on the vertical median line thereof. In one side of said body of said reservoir, midway between the ends is formed an opening of a substantially large diameter which is defined by a flange or neck 17 having diametrically oppositely disposed pins 17a—17a.

Said flange or neck constitutes the filling and clean-out opening for the reservoir when said reservoir is so disposed as to bring

said neck on the top side thereof and it also constitutes the discharge opening for the reservoir when the same is so disposed as to bring said neck on the bottom side 5 thereof as will later appear. Associated with said neck is a loose fitting cap 18 which is formed with bayonet slots to be removably engaged with the pins 17^a—17^a on said neck. Said cap also carries a breather or 10 air tube 19 of a length approximating the diameter of the body of the reservoir.

The drinking pan 3 which is rectangular in plan is of a comparatively shallow depth and is of a length and width approximating 15 the length and diameter of the reservoir. Said pan is so formed as to provide a flange 20 at each end which is adapted, when the fountain is assembled, to engage upon and be detachably secured to a pair of the ears 20 10 of an associated end plate by means of bolts and nuts 21.

In assembling the fountain which is delivered to the purchaser in a knocked down condition, the end plates are stood upright 25 and the pan 3 is then attached to the ears thereof by the bolts and nuts 21. This provides a partly assembled structure capable of standing alone ready to receive the reservoir. The top ends of the end plates are 30 then spread apart (the ears 10 flexing to permit the same) after which the trunnion on one end of the reservoir is inserted in one opening 7 of an end plate and the other trunnion is inserted in the opening 7 of the 35 other end plate. The top ends of said end plates are then moved inwardly toward the respective ends of the reservoir and a removable locking pin 22 is then inserted through transverse openings provided therefor in 40 the outer end of each trunnion. Said pin which appears somewhat as a shepherd's crook, is best shown in Fig. 6, consists of a straight end portion 23 and a crooked end portion 24. When the straight end portion 45 is inserted through the openings in the associated trunnion, the extremity of the crooked end will engage in a depressed seat 25 in the end wall of the trunnion and as said pin is longer than the diameter of the openings 50 7—7, it follows that said trunnions cannot be accidentally displaced from said openings.

The reservoir may now be turned to bring 55 those flat sides of its trunnion into engagement with the flat bottom parts of the openings 7—7 in the end plates to bring the neck of the reservoir on the top side of the same as best shown in dotted lines in Fig. 3. Thus access may be had to the interior of the reservoir for cleaning and filling.

60 When the reservoir is filled the cap is applied to the neck and then given a short turn to engage the bayonet slots 18^a thereof with the pins 17^a on said neck, the breather or air tube extending down into said reservoir. With the cap in place, the reservoir

may be turned on its trunnions to bring the cap to the bottom side thereof so that with the loose fit of the cap, water runs out from about the cap into the drinking pan. As the water thus runs out from the reservoir, air 70 will enter the reservoir through the tube 19. When the proper water level has been attained in the pan, the bottom end of the tube is sealed by the water and no more water can flow from the reservoir into the 75 pan.

As the water level in the pan falls, due to evaporation or to its being consumed by the poultry or animals drinking from the pan, air will gurgle into the tube 19 and 80 water will then trickle from about the cap until that water level in the pan is restored which will seal off the cap again. Thus water is admitted to the pan only as required to keep it full, the animals or poultry 85 drinking from opposite sides of the pan.

By reason of the flat sided trunnions the reservoir will stand as desired, either with the neck at the top or bottom until manually changed. The fountain consists of 90 but a few parts which may be shipped knocked down to save shipping space and may be readily assembled.

It feeds water only as needed and may 95 be readily cleaned and refilled and is therefore sanitary.

While in describing the invention, I have referred in detail to the form and arrangement of the various parts thereof, the same 100 is to be considered as by way of illustration only and therefore I do not wish to be limited thereto except as may be pointed out in the appended claims.

I claim as my invention:

1. A drinking fountain embodying therein end members, a drinking pan supported thereby, a reservoir above the pan having a filling neck, a cap operatively connected to said neck, a coacting means on said end members and reservoir respectively providing a bearing for the reservoir, which coacting means include trunnions and bearing openings therefor having engaging flat sides and removable means extending through said 110 trunnions and arranged to engage the outer face of the top ends of said end members to prevent displacement of said trunnions in said openings and the spreading apart of said top ends of said end members. 115

2. A drinking fountain embodying therein end members, a drinking pan supported thereby, a reservoir above the pan having a filling neck, a cap operatively connected to said neck, an axially disposed, flat sided trunnion on each end of the reservoir adapted 125 to engage in a flat sided opening in said end member and a removable locking pin extending through each trunnion outside the end member and having a portion engag- 130

ing the end of the trunnion to hold the same against displacement relative to its associated end member.

3. A drinking fountain embodying there-in end members, a drinking pan extending between and supported by said end members, a reservoir having a filling neck, trunnions on each end of said reservoir bearing in openings in said end members, said trunnions and openings having flat portions co-acting so as to hold the reservoir with the neck either at the top side of the reservoir or at the bottom side thereof to discharge into said pan and a cap operatively connected to said neck to automatically control the flow of water from said reservoir into said pan.

4. A drinking fountain embodying there-in, sheet metal end members, each having a bearing opening in its top end with a flat bottom side and each having at least one part punched inwardly to form a support, a pan having end flanges adapted to engage upon and be secured to said support, a reservoir having a filling neck in one side, a trunnion on each end of said reservoir and having flat sides to engage with the flat side of said bearing opening to hold the reservoir in position with the neck at either the top or the bottom thereof, and a cap for controlling the flow of water from the reservoir into said pan when said neck is on the bottom side of said reservoir.

5. In a drinking fountain a reservoir having a neck, a cap detachably secured to said neck with a loose fit with respect to said neck, and an air tube carried by the cap and extending into the reservoir.

In testimony whereof, I have hereunto set my hand this 31st day of July, 1928.

ADOLPH R. HOEFT.
